CLAIM

The ornamental design for an electrical card connector, as shown and described.

DESCRIPTION

FIG. 1 is a front, top and right side perspective view of an electrical card connector showing my new design;

FIG. 2 is a right elevational view thereof;

FIG. 3 is a left elevational view thereof;

FIG. 4 is a rear elevational view thereof;

FIG. 5 is a front elevational view thereof;

FIG. 6 is a top plan view thereof;

FIG. 7 is a bottom plan view thereof; and,

FIG. 8 is a right side elevation view thereof, on a larger scale.

The broken line in the drawing views showing of the internal elements is for illustrative purposes only and forms no part of the claimed design.
